SUPPORTING SPACER FOR ANNULAR CORRUGATED FINS

Sven Holm, Wellsville, N. Y., assignor to The Air Preheater Corporation, New York, N. Y.

Application March 8, 1952, Serial No. 275,505

5 Claims. (Cl. 257—246)

1

This present invention relates to heat exchange apparatus and particularly to extended surface for tubes or the like through which one fluid is circulated in heat exchange relationship with another.

Numerous heat exchangers have been proposed in which one fluid is confined to a determined path flow as by directing it through the annular space between a pair of concentric tubes while the other fluid flows through the smaller of the concentric tubes. To increase the efficiency of heat transfer between the fluid flowing in this tube and that traversing the aforesaid annular passage, longitudinal fins are frequently provided on the tubes with the fins extending radially in good heat transfer relationship with one or both tubes.

In one proposed method of providing such a heat exchange element with extended surface it has been proposed to corrugate a sheet and insert it with the corrugations extending longitudinally of the tubes in a radial position between the inner and outer tubes and with the crests and dwells of the corrugations in contact with these two tubes. To obtain a good heat transfer both without welding or brazing it has been proposed to physically expand the inner of the two tubes after the corrugated fin has been mounted in the annular space and to enable this to be done it has been suggested that a metal should be used for the fin which is not distortable.

It has nevertheless been found most difficult in practice to expand the inner tube to wedge the corrugated fin into contact with both inner and outer tubes without effecting some distortion of the folds of the corrugated fin. The present invention contemplates the provision of supporting sleeves or collars mounted in cooperative relation with the folds of the fin so as to sustain and render it more rigid.

The invention will be best understood upon consideration of the following detailed description of the illustrative embodiments thereof when read in conjunction with the accompanying drawings in which:

Figure 1 is a perspective view of a portion of a tubular heat exchange element embodying the present invention;

Figure 2 is a transverse sectional view of an earlier form of heat exchange unit comprising a pair of concentric tubes with radial fins in the annular space through which one fluid flows in heat exchange relationship with another traversing the interior of the smaller tube;

Figure 3 is a partial view similar to Figure 2

2 showing the effect of expansion of the inner tube on the folds of the corrugated fin when the inner tube is expanded to wedge the crests and dwells of the fin element in good physical contact with the tube surfaces;

Figure 4 is a fragmentary longitudinal sectional view corresponding to Figure 2;

Figures 5 and 6 show alternative forms for the supporting and reinforcing sleeve associated with the corrugated fin.

In Figure 1 there is shown a form of heat exchanger in which one of the fluids passes through the interior of a tube 10 in heat exchange relationship with another fluid that flows in the annular space 11 defined by a second tube 12 concentric with the tube 10. One form of extended surface for a heat exchanger of this type comprises a corrugated sheet 13 bent to circular form and fitted into the annular space 11 with the outer faces of the crests 14 and dwells 15 of the corrugations in contact with the confronting cylindrical surfaces of the tubes 10 and 11. The corrugated elements 13 extend longitudinally of the annular passage 11 and the folds 16 of the corrugated element extend radially from the inner tube 10 to the outer tube 12. To obtain a good physical heat transfer contact between the fin element 13 and the walls of the tubes 10 and 12 it has been proposed heretofore to expand the inner tube 10 (Figure 2) as by means of a mandrel so as to exert a thrust in a radially outward direction on the folds 15 on the corrugated element 13. It has also been proposed that the fin element 13 be made of a suitable metal such that the folds 16 would not buckle or become distorted in their major portions due to the exertion of the radial force imposed thereon by expansion of the tube 10. Nevertheless, it has been found that in addition to some distortion of the crest and dwell portions 14, 15 of the corrugations to wedge them against the surfaces of the tubes 10 and 12, the radial force resulting from expansion of the tube 10 produces distortion of the folds 16 that extend radially and also causes some displacement of them in a circumferential direction as illustrated in Figure 3.

Considerable difficulty has been experienced in preventing the fin section from deflecting when the inner tube is expanded. This condition is shown in Figure 3. It is obvious that the contact pressure desired is not obtained unless the fin sections are kept in a substantially radial position.

The invention as illustrated in Figure 1 is an

improvement in the construction of a finned tube shown in Figures 2 and 3 and contemplates preventing the fin sections 13 from deflecting. In forming the fin sections 13 there is a limit to length that can be formed so that in a long tube several sections are required as shown in Figure 4. In sliding the fin sections 13 into the annular space 11, a serrated ring 20 as shown in Figures 4 and 6 is placed between each section 13 and after completing the tube, one or more prongs 23 on the outside rings 25 (Figure 5) are bent and brazed to the inner tube 10. This is shown at 24 in Figure 4. The prongs 23 of ring 25 are tapered so as to have a wedge effect between the folds 16 of fin elements 13. The ring 20 has serrations 21 of a width slightly greater at their ends than the thickness of fin material. The serrated ring 20 should preferably be placed between sections 13 and pronged ring 25 at each end.

In accordance with the present invention distortion of the fin elements 13 is prevented by providing this collar or sleeve 20 which is provided with serrations 21 on its circumferential edges as shown in Figure 6 or with prongs 23 as shown in Figure 5. The prongs 23 are spaced so that they fit snugly between the folds 16 of the corrugated element 13 in the plane in which the ring 25 is mounted. As is more clearly shown in Figure 4, the rings or sleeves 20, 25 are slightly larger in diameter than the inner tube 10 of the two concentric tubes so that the serrations 21 or prongs 23 become inserted between the folds 16 of the corrugated element 13 somewhere near the mid-point of their radial extent. Figure 4 also illustrates that where the fins 13 are interrupted longitudinally of the tube, the serrated sleeve 20 fits between and mutually interconnects two adjacent fin elements. The pronged sleeves 25 mounted at the extreme ends of the fin elements at the outer ends of the tubes have some of the prongs bent into contact with the surface of the tube 10 so that they may be brazed thereto as shown at 24 in Figure 2.

What I claim is:

1. In a heat exchanger having a pair of tubular members spaced in concentric relation to form an annular fluid passage; a heat transfer fin member in said passage comprising; a sheet member formed with a plurality of generally rectangular corrugations and bent to circular form with the corrugations extending parallel to the axis of said tube and the yokes or webs thereof between the side faces of the folds of the corrugations in contact with one or the other of said tubes and the said face portions extending

radially between said tubes as fins; and a collar having circumferentially extending edges serrated with the teeth or serrations fitting in the intervals between the folds of said corrugated sheet to maintain the said face portions thereof properly circumferentially spaced and in radially extending relation between said tubes.

2. A heat exchanger as recited in claim 1 wherein said collars are serrated on both circumferential edges to engage between a pair of corrugated members on said tubes.

3. In a heat exchanger having a plurality of concentric tubular members nested to form an annular fluid passage; heat transfer fin member in said passage comprising a corrugated sheet member formed with a plurality of generally rectangular corrugations and bent to circular form with the corrugations extending parallel to the axis of said tube and the yokes or webs between the folds or longitudinal faces of the corrugations in contact with one or the other of said tubes and the fold portions extending radially between said tubes; and a sleeve mounted at each end of said corrugated member adjacent the tubular member, said sleeve having a serrated circumferentially extending edge with the teeth or serrations fitting in the intervals between the folds of said corrugated member to maintain the folds properly circumferentially spaced between the tubular members and in radially extending relation between said tubes.

4. A heat exchanger as recited in claim 3 wherein the teeth on said serrated collar are disposed in a circle having a diameter sufficiently greater than that of the smaller of said tubular members as to engage between folds of a corrugated member on said tubular member so as to cause alternate teeth to engage the outer faces of the alternate yokes of the corrugations which are in engagement with said smaller tubular member.

5. A heat exchanger as recited in claim 3 wherein said serrated collars have convergently tapered teeth that at their roots are of somewhat greater width than the yoke portions of the corrugation folds between which they engage so as to wedge therebetween.
